UNITED STATES PATENT OFFICE.

HARRY J. HARSHBERGER, OF TIPPECANOE CITY, OHIO, ASSIGNOR TO THE TIPP WHIP COMPANY, OF TIPPECANOE CITY, OHIO, A CORPORATION OF OHIO.

COATING FOR SOAP.

1,325,361.

Specification of Letters Patent.

Patented Dec. 16, 1919.

Application filed January 27, 1919. Serial No. 273,315.

To all whom it may concern:

- Be it known that I, HARRY J. HARSHBERGER, a citizen of the United States, residing at Tippecanoe City, in the county of Miami and State of Ohio, have invented certain new and useful Improvements in Coating for Soap, of which the following is a specification, reference being had therein to the accompanying drawing.
- 10 This invention relates to an improved coating for soap, and has for its particular object to provide an improved coating for shaving soap sticks commonly put up in metal containers.
- 15 The primary object of my invention is to provide a coating which will effect complete sanitation in the use of the soap thereby avoiding the possible dangers of infection resulting from corrosion which is a common fault of metal soap containers.
- 20 To this end I provide a coating of paraffin applied direct to the body of the soap and therefore conforming exactly to the shape of the stick. Both ends of the soap,
- 25 as well as the cylindrical body portion may be covered with paraffin, but in its preferred form the end of the stick from which the soap is used is left exposed ready to be used as delivered to the purchaser.
- 30 An important advantage is realized in the use of shaving soap put up in this manner in that the paraffin coated stick may be rinsed after use without any portion of the soap, except the exposed end thereof, being
- 35 exposed to moisture, the paraffin being impervious to or insoluble in water at the usual temperature for toilet use. Thus the main body of the soap is kept entirely dry and complete sanitation may be effected.
- 40 It is understood, of course, that shaving soap in the well known form of long cylindrical sticks is applied direct by rubbing the end of the stick over the surface to be lathered, the stick in the ordinary
- 45 metal container being pushed upwardly by any suitable arrangement, such as an adjustable bottom in the container.

With the use of my improved coating such an arrangement is not necessary, as the exposed edge of the paraffin will reduce proportionately with the soap in the application thereof, the edge of the paraffin coating remaining substantially flush with the applica-

tion surface of the soap until the entire stick is consumed.

55

My invention, obviously, has the advantage of simplicity, cheapness, attractiveness and what is more important convenience and sanitation in use. Without change or adjustment the soap is always ready for use, and by merely rinsing the stick it is again prepared for after use. The body of the soap always being dry there is no waste and due to the protection afforded by the perfectly sanitary paraffin coating there is no possibility of infectious substances, such as may result from corroded metal, being conveyed to the soap.

An incidental advantage of my invention, made possible by the transparency of the paraffin coating, consists in the means it affords for securing a label or trade mark to the body of the soap, preferably to the unused end of the soap. The label is not obscured by the paraffin coating over it, and being protected by the paraffin will be preserved until the entire stick is used.

The paraffin or coating of other similar material may be applied to the soap in any suitable manner, as by dipping or immersing the cakes of soap in a bath of fluid material whereby an even coating of the material will adhere to the soap and when cooled will condense and form the protecting coating as contemplated in the invention.

80 Referring to the drawings,

Figure 1 is an end view of the paraffin coating as applied to a stick of shaving soap;

90

Fig. 2 is a longitudinal cross sectional view of a stick of soap having the paraffin coating applied thereto;

Fig. 3 is a cross sectional view taken on the line 3-3 of Fig. 2; and

95

Fig. 4 is an end view of the invention showing the manner of securing a label to the soap under the paraffin coating.

As here shown the invention is in the form of a stick of shaving soap 1, contained within a coating of paraffin 2.

While it has been stated that one end of the soap is preferably left uncoated or exposed, it is, of course, obvious that both ends may be coated over with the paraffin, it being then necessary for the user to remove the

paraffin from one end of the stick before the first application of the soap is made.

In Fig. 4 of the drawings the manner of displaying a label or trade mark on the soap is shown.

While paraffin is a suitable material to use to realize the purposes of the invention, other materials having similar qualities may also be used and satisfactory results obtained therewith; the essential qualities being found in materials that are impervious to water within a normal range of temperatures; that will conform and adhere to the surface of the soap; that will reduce readily with the working surface of the soap; that will keep the body of the soap dry and protect it against contact with infectious substances; that will be suitable to serve as a commercial covering for the soap; that will be inexpensive, attractive in appearance and convenient and sanitary in use.

While the normally white paraffin in semi-hard or plastic form is ordinarily the preferred material to be used, it may be desirable for special purposes, as in the preparation of sales or display samples, or to distinguish different grades of soap, etc., to use variously tinted paraffin which would add variety and attractiveness to the soap sticks for commercial effect.

As far as I am aware I am the first to discover and apply an invention having essentially the features of construction and application of the present invention. I do not wish to be limited, therefore, to the details as herein disclosed and described, but wish to claim broadly, as defined and comprehended in the appended claims, the principles and essentials of the invention as well as the specific organization and arrangement thereof. The impervious materials as treated in the claims are used in a qualified sense having reference to paraffin or like material which is normally insoluble to the influence of water, that is, at the temperatures at which water is ordinarily used for toilet purposes.

Having thus fully described my invention,

what I claim as new and desire to secure by Letters Patent, is:—

1. The combination, with a cake of soap having an end adapted to be immersed in water from which the soap is applied by rubbing the same on the skin to be treated thereby, a coating of impervious material formed integral of said cake and terminating in edges substantially flush with said end portion, and reducible equally with the surface thereof in the application of said soap. 50

2. The combination, with a stick of soap, 60 a coating of impervious material covering the body and one end thereof adapted to prevent soap coming in contact with the hand and terminating in an edge substantially flush with the opposite end of said stick, and reducible equally with said end in the application of soap therefrom. 65

3. The combination, with a stick of shaving soap, a coating of impervious material covering the body and one end thereof 70 adapted to prevent soap coming in contact with the hand and terminating in an edge substantially flush with the opposite end of said stick and reducible therewith incident to a rubbing application of said end to the 75 skin treated thereby.

4. The combination, with a stick of shaving soap, a coating of semi-plastic impervious material covering the body and one end thereof adapted to prevent soap coming 80 in contact with the hand and terminating in an edge substantially flush with the opposite end of said stick and reducible therewith incident to a rubbing application of said end to the skin treated thereby. 85

5. The combination, with a stick of shaving soap, a coating of semi-plastic impervious material conforming and adhering to the body and one end of said stick and terminating in an edge substantially flush with the opposite end of said stick and adapted to be immersed in water reducible therewith incident to a rubbing application of said end to the skin treated thereby. 90

In testimony whereof, I affix my signature. 95

HARRY J. HARSHBERGER.
